SEAL

Winfred M. Brooks, West Orange, N. J., assignor
to E. J. Brooks Company, Newark, N. J., a corporation of New Jersey

Application April 14, 1950, Serial No. 155,932

5 Claims. (Cl. 292—310)

1

This invention relates generally to seals of sheet material comprising two main sections, bendable toward one another and having at their outer ends means for interengaging when closing the seal. Such means consist, in part, of a prong carried by one of the main sections, and the main object and feature of this invention is to prevent premature rupture of the prong when closing the seal. Another feature of the invention resides in providing positive means that will assure a complete closure of the seal and which will render it more difficult than heretofore to reopen and reclose the seal.

Figs. 1 to 8 inclusive show one preferred form of the invention;

Fig. 1 is a view in front elevation looking in the direction of arrow 1 of Fig. 2, the seal being in open position;

Fig. 2 is a view looking in the direction of arrow 2 of Fig. 1 with parts broken away and in section;

Fig. 3 is a transverse sectional view substantially on the plane of line 3—3 of Fig. 2;

Fig. 4 is a plan view looking substantially in the direction of arrow 4 of Fig. 5 showing the seal in its closed position;

Fig. 5 is an enlarged scale sectional view substantially on the plane of line 5—5 of Fig. 4;

Fig. 6 is a fragmentary view of the prong member carried by one of the main sections before it is partly bent;

Fig. 7 is a fragmentary sectional view substantially on the plane of line 7—7 of Fig. 6;

Fig. 8 is a fragmentary sectional view substantially on the plane of line 8—8 of Fig. 6;

Figs. 9 to 14 inclusive show a second preferred form of the invention;

Fig. 9 is a view in front elevation looking in the direction of arrow 9 of Figure 10, and showing the seal in its open position;

Fig. 10 is a view looking in the direction of arrow 10 of Fig. 9 with parts broken away and in section;

Fig. 11 is a plan view looking in the direction of arrow 11 of Fig. 10 showing the seal in its closed position;

Fig. 12 is a sectional view substantially on the plane of line 12—12 of Fig. 11;

Fig. 13 is an enlarged detail sectional view of the outer ends of the main sections, the seal being shown in its closed position;

Fig. 14 is an enlarged detail view of the prong member shown in Fig. 9;

Figs. 15 through 17 show a third preferred form of the invention;

2

Fig. 15 is a view in front elevation, looking in the direction of arrow 15 of Fig. 16, showing the seal in its open position;

Fig. 16 is a view looking in the direction of arrow 16 of Fig. 15; and

Fig. 17 is an enlarged sectional view of the outer end of the main sections, the seal being shown in its closed position.

Referring first to the form of the invention shown in Figs. 1 through 8, the seal here comprises two main sections 25 and 26 bendable toward one another and having, at their free ends, means to interengage in closing the seal. As here shown, these means consist of a prong 27 and a tongue 28 having an opening 29 for the reception of prong 27.

The seal is sold and shipped in the form shown in Figs. 1 and 2, that is: tongue 28 lies bent over main section 26 into the final position it is intended to occupy; whereas prong 27 lies only partly bent under its main section 25, and will be bent still further when the seal is closed, as indicated in Fig. 5. It is, of course, impossible to prevent reopening of the closed seal, but it is possible to leave evidence that the seal has been tampered with in that, upon unbending prong 27, the material thereof is ruptured and prong 27 breaks off so that the seal cannot be reclosed. But, as prong 27, in closing the seal, has to be bent very sharply, it sometimes occurs that, in closing the seal, prong 27 breaks off, in other words: the seal no longer functions as such. It will be understood that it requires a very delicate balance in the formation of the parts of the seal, on the one hand, to prevent premature rupture of prong 27 and, on the other, to assure that rupture will occur upon reopening of the closed seal.

It has been found that the above-described difficulty can be overcome by compelling prong 27 to bend, in closing the seal, on a bending line different from that on which it is partly bent before closing the seal. To this end prong 27 is provided with a relatively rigid zone 30 and a relatively weakened zone 31, the latter located outwardly beyond said relatively rigid zone. The initial bending of prong 27 into the position shown in Figs. 1 and 2 is made on a bending line in the relatively rigid zone, whereas the bending operation, in closing the seal, is compelled to take place on a bending line in the relatively weakened zone. If desired, the relatively rigid zone may be further stabilized by providing main section 25 with a strengthening bead 32.

One general aspect of the importance of pre-

venting premature rupture of the material of prong 27 has been already alluded to. The form of the invention shown in Figs. 1 through 8 is a seal for use in connection with meat or poultry, and it will be evident that premature rupture of prong 27 may have serious consequences if the prong were to be swallowed by the person consuming the food. In fact, in the case of a meat or poultry seal, this phase of the matter is of greater importance than failure to seal the food.

In the form of the invention shown in Figs. 9 through 14, the seal is composed of two main sections 33 and 34 bendable toward one another at junction-line 35. Here, again, main section 33 is provided with a prong 36 lying partially bent, before closing the seal, on a bending line in a relatively rigid zone 37 which may be additionally stabilized by providing a transverse lip 38. 39 indicates the relatively weakened zone, so that, in closing the seal, said prong 36 will be compelled to bend on a bending line passing through said weakened zone. Main section 34 is provided with a tongue 40 lying bent over said main section, and tongue 40 is provided with an opening 41 for the reception of prong 36. Prong 36 is here provided with a latch 42 which engages lower end 43 of tongue 40 when the seal is closed.

In this instance, main sections 33 and 34 are provided with side-walls 44 and 45 which overlap in closing the seal. The seal is here intended to receive a strand of flexible material 46 at junction-line 35. Sometimes this strand is coarse, or double as shown, and may therefore prevent the means (prong 36 and tongue 40) at the free ends of the main sections from interengaging properly, and may prevent proper closing of the seal. To overcome this difficulty, walls 44 and 45 are provided at their opposed edges with complementary cams 47 and 48 that move strand 46 away from junction-line 35, as indicated in Figs. 11 and 12, to thereby enable the seal to be properly closed.

Turning now to the third form of the invention disclosed in Figs. 15 through 17, 47 and 48 indicate the two main sections, 49 is the prong carried by main section 47 and bent, before the seal is closed, on a bending line passing through relatively rigid zone 50, said prong being provided with a weakened zone 51 so that, when closing the seal, said prong will be compelled to bend on a bending line in said relatively weakened zone. Carried by main section 48 is a tongue 52 that lies bent inwardly over main section 48 in spaced relation thereto, said tongue having an inner-lip 53 that lies in engagement with the inner-wall of main section 48. 54 indicates an opening in tongue 52 through which prong 49 enters when the seal is being closed, and said tongue 52 has a second opening 55 that lies in front of lip 53. When the seal is being closed, prong 49, after entering opening 54 of tongue 52, will be deflected by engagement with the inner-wall of main section 48, and will thereafter protrude through second opening 55 of said tongue. If desired, prong 49 can be provided with a latch 56 that engages one of the walls of second opening 55 to prevent retraction of said prong. It will be observed that, if it is attempted to insert an implement such as a screwdriver through opening 54 in an endeavor to release prong 49, the effort to open the seal will be rendered more difficult by reason of the fact that, when attempting to raise said prong 49, said prong will carry with it tongue 52 because said prong pro-

jects out through opening 55. To facilitate the above-described behavior of prong 49, main section 48 can be shaped so as to provide a pocket 57 thereby not only assuring the provision of a space between tongue 52 and said inner-wall but also to properly deflect prong 49 toward second opening 55.

The feature of providing a combined finger guard and auxiliary deflecting surface X shown in the several forms of the invention, and indicated by way of example in Figs. 1, 2, 4 and 5—whereby prong 27, if outwardly misdirected, will be deflected by said combined finger guard and deflecting surface so that prong 27 will enter through opening 29 of tongue 28—is not claimed in the present application but forms the subject matter of a prior application, Ser. No. 117,219, filed September 22, 1949.

I claim:

1. In a seal of sheet material comprising two main sections, to receive between them at their junction-line a strand of flexible material, said main sections bendable toward one another on said junction-line and having means adjacent their outer ends to interengage when closing said seal, said main sections having side-walls that overlap when the seal is closed and which are provided with complementary cam-shape edges to move said strand away from said junction-line to enable said means adjacent the outer ends of said main sections to fully interengage when closing the seal.

2. In a seal having two bendably connected main sections of sheet material, the combination with one of said main sections of a tongue formed integrally therewith and bent inwardly thereto in spaced relation thereto and having an inner-lip that lies in engagement with the inner-wall of said main section, said tongue having an opening adjacent its line of bending and having another opening intermediate said inner-lip and said first-mentioned opening; and in combination with the other of said main sections of a prong integrally formed therewith lying partly bent under its main section to enter the first-mentioned opening in the tongue of said first-mentioned main section when the two sections are bent toward each other, said prong of the second main section adapted to be deflected by the inner-wall of said first-mentioned main section and thereafter to protrude through the second opening of said tongue.

3. In a seal having two bendably connected main sections of sheet material, the combination with one of said main sections of a tongue formed integrally therewith and bent inwardly thereto in spaced relation thereto and having an inner-lip that lies in engagement with the inner-wall of said main section, said tongue having an opening adjacent its line of bending and having another opening intermediate said inner-lip and said first-mentioned opening; and in combination with the other of said main sections of a prong integrally formed therewith lying partly bent under its main section to enter the first-mentioned opening in the tongue of said first-mentioned main section when the two sections are bent toward each other, said prong of the second main section adapted to be deflected by the inner-wall of said first-mentioned main section and thereafter to protrude through the second opening of said tongue, and said prong having a latching member that engages a wall of the second opening of said tongue to prevent retraction of said prong.

4. In a seal of sheet material comprising two main sections to receive between them, at their junction-line, a strand of flexible material, said main sections bendable toward one another on said junction-line and having means adjacent their outer ends to interengage when closing said seal, a prong forming part of said means, said prong lying, before closing the seal, bent partly under that main section by which it is carried, said prong having a weakened zone to compel it to bend, in closing the seal, on a bending line different from that on which it was partly bent before closing the seal, and said main sections having side-walls that overlap when the seal is closed and which are provided with complementary cam-shape edges to move said strand away from said junction-line to enable said means adjacent the outer ends of said main sections to fully interengage when closing the seal.

5. In a seal of sheet material comprising two main sections bendable toward one another and having means adjacent their free ends to interengage when closing the seal: a tongue, forming part of said means, carried by one of said main sections and lying bent inwardly over the main

10
1520
25

section that carries it, said tongue having an opening, adjacent its bending line to receive, when closing the seal, a prong carried by the other of said main sections; a prong, also forming part of said means, carried by the other of said main sections, said prong lying, before the seal is closed, partly bent throughout its length under the main section that carries it, said prong having a weakened zone, closely adjacent its original bending line, to compel it to bend in said zone substantially throughout its length, in closing the seal, by engagement with said first-mentioned main section after entering the opening in said tongue.

WINFRED M. BROOKS.
